SNAP SWITCH

John O. Roeser, Park Ridge, Ill., assignor to Illinois Tool Works Inc., Chicago, Ill., a corporation of Delaware
Filed Dec. 20, 1961, Ser. No. 160,828
8 Claims. (Cl. 200—67)

This invention relates in general to control devices for electrical circuits and more particularly relates to control devices of the snap acting variety.

It is a general object of this invention to provide a snap acting electrical control device which has a minimum number of parts, is easy to manufacture, and is well adapted for the purposes of switching electrical currents.

A further object of this invention is to provide a snap acting switch wherein the switch body is made of a tough plastic material which is relatively rigid in thick section and which is relatively flexible in thin section, whereby the actuator and the body portion of the switch may be molded in a one piece unit.

It is a further object of this invention to provide a snap acting switch which has an electrically conductive blade portion which serves the dual function of providing snap action to the movable contact and retaining the actuator in operative relationship thereto.

It is a further object of this invention to provide a switch of the characteristics above set forth which is formed of a thermoplastic material wherein the terminals and/or any electrical conductive parts may be heat sealed into operative relationship on the switch body.

The novel features that are characteristic of the invention are set forth with particularity in the appended claims. The invention itself, however, both as to its organization and its method of operation, together with additional objects and advantages thereof, will best be understood by the following description of specific embodiments when read in connection with the accompanying drawings in which:

FIG. 1 is a top plan view of one form of the invention;
FIG. 2 is a side elevational view along lines 2—2 of FIG. 1;

FIG. 3 is a sectional view along lines 3—3 of FIGS. 1 and 2;

FIG. 4 is a plan view of one of the components shown in FIGS. 1 and 2;

FIG. 5 is an enlarged fragmentary view of a portion of FIG. 2;

FIG. 6 is an isometric perspective view of the components in an alternate form of switch construction embodying the inventive concepts;

FIG. 7 is a view, similar in many respects to FIG. 2, showing another alternate form of the invention; and

FIG. 8 is a sectional view along lines 8—8 in FIG. 7.

The switch 10 comprises the body means 12, a flexible blade means 14 carrying the movable contact and providing the common terminal of the switch as well as providing the snap action, a first fixed contact means 16, and a second fixed contact means 18.

The body means 12 is preferably formed of a tough durable moldable thermoplastic which has insulating characteristics and which is relatively rigid in relatively thick section and is relatively flexible in relatively thin section. One material suitable for this purpose is a polycarbonate plastic manufactured by General Electric Co. and sold

2

under the trademark Lexan. The body means 12 essentially comprises a base portion 20 which is of a thickness in cross-section to provide a relatively rigid construction having a raised integral lug portion 22 at one end thereof. 5 The top surface 24 of lug 22 is essentially flat and spaced a predetermined distance above the base portion 20. At the other end of the body means 20 is a second integral raised or elevated lug portion 26 having an integral arm 28 which terminates in a free end 30. It will be noted 10 that arm 28 is integral with the body 20 and in fact the whole body means 12 is adapted to be molded as a single part. The arm 28 is relatively narrow in width and has a varying vertical cross-sectional dimension to provide a flexing hinge portion 32 adjacent to upstanding end lug 15 26 to impart movability to the free arm 30. In essence, portion 32 provides the function of a hinge and due to the increase in cross-section of arm 28 as it progresses towards its free end 30, the arm 28 essentially acts as a lever arm and is relatively rigid except at the hinge 20 point 32.

By molding arm 28 in an upright position (at substantially right angle to the base portion 20) and then in assembly, deflecting the arm downwardly for assembly to the blade means 14, the arm 28 will be biased upwardly 25 by the internal stresses therein. It will be noted that arm 28 after assembly to the blade means 14 is substantially parallel with the body portion 20 and is substantially aligned with the longitudinal axis of body portion 20. The arm 28 has a length slightly shorter than the body 30 portion 20 and terminates short of raised lug 22 so that the free end portion 30 will not interfere with lug 22 upon vertical downward movement thereof from the position shown in FIG. 2 and its subsequent return.

The free end 30 of arm 28 is formed with an actuator 35 engageable cam lug surface 34 on the upward side thereof as viewed in FIGS. 2 and 5, and is formed with a depending portion 36. A longitudinally extending lug portion 38 is formed at the bottom of depending lug 36 which extends in the direction of body lug portion 22. On the 40 opposite side of depending portion 36, a somewhat V-shaped groove 40 is formed for assembly purposes hereinafter appearing.

The electrically conductive blade means 14 may be 45 formed of thin flexible material, for example, beryllium copper, and may have an initially flat generally rectilinear shape. By a suitable stamping operation, a central tongue 44 may be blanked out of the blade means in a manner to provide a pair of spaced arms 42 of the configuration as shown in FIG. 4. A blade mounting aperture 46 may be 50 formed in the body of blade means 14 in a position essentially opposite the end 52 of the tongue 44. A tab 48 having an aperture therein for electrical connection to suitable wires is provided at one end of the blade body. The movable contact 50 is disposed on the blade means 55 on the end opposite to tab 48. There are many ways of mounting the blade means 14 to the switch body means, one such being the molding of an integral lug 54 which will project through aperture 36 of the blade means 14 and then heat sealing and squashing down the lug to 60 fixedly mount the blade in position on the switch.

After the blade means 14 is mounted to lug surface 24, the end surface 52 of tongue 44 is disposed in notch 40 on the underside of the free arm 28 of the body means as shown in FIGS. 2 and 5. Lug surface 38 is inserted

underneath the blade means and is retained by interference therewith as shown. The tongue 44 is bowed and is under compression so as to exert tension on the arms 42. Movement of the free end 30 of the body means about hinge point 32 will cause the movable contact 50 on the blade means to move with a snap action between the upper and lower fixed contacts 18 and 16.

The fixed contact 16 may be of any suitable type, one type being shown as a metal stamping having a depending portion 56, a notch portion 58, and a horizontal portion 60. The notch portion 58 fits into a suitable recess formed in the side of the body means base portion 20 and may be retained in position by any number of means, one such being heat sealing by projecting portions of the body over the notched out portion 58. The horizontal surface 60 becomes the lower fixed contact of the switch. The other fixed contact 18 is substantially similar except that horizontal portion 64 is located above the depending portion 62 to provide the upper fixed contact. Fixed contact 18 may be retained in the same manner as fixed contact 16 and is disposed on the other side of the switch body. Both of the fixed contacts 16 and 18 may have suitable holes 66 in the respective depending portions 56 and 62 to aid in attachment of suitable electrical circuitry.

A modified form of the invention is shown in FIG. 6 and similar parts will be identified with similar reference numerals with the addition of the suffix *a*. Switch 10*a* is essentially similar in the method of mounting the fixed contacts 16*a* and 18*a* and in overall configuration of the body means 12*a*. A different type of blade means 14*a* is employed. Blade means 14*a* differs in that the two arms 42*a* on either side of the central tongue are completely separate from the central tongue 44*a* and are shorter in length. The central tongue 44*a* extends sufficiently so as to afford the aperture 46*a* to be fitted over mounting lug 54*a* which has an undercut surface adjacent surface 24*a* so as to retain the tongue 44 in fixed relationship to the switch body. The end surfaces 68 of the arms 42*a* are disposed in notches 70 formed in the body means lug portion 22*a* as shown. Due to the relative positioning of the aperture 46*a* and the length of the arms 42*a*, the tongue portion 44 is put into tension and the arms 42*a* are predisposed into a sinusoidal wave by the raised lugs 72 on the switch body. The free end 30*a* of arm 28*a* is formed with thin lips 74 which fit over the central tongue 54 and retain the head portion in operative engagement with tongue 44. The channel 76 so formed in the underside of the free end 30*a* traps the tension arm 34 and depression of the head 34 causes the contact 50*a* to move between the fixed contacts 16*a* and 18*a*.

Still another modified form of the invention is shown in FIGS. 7 and 8 and similar parts shall be identified with similar reference numerals with the addition of the suffix *b*. The form of switch 10*b* shown in FIG. 7 is basically similar to that shown in FIG. 1 except for the following differences. The hinge portion 32*b* of switch 10*b* is offset closer to the midpoint of the switch so as to give a thickened portion 84 adjacent to upstanding switch body lug 26*b*. Thus, electrical terminals in the forms of wires 80 and 82 may be disposed in operative engagement with printed contacts 86 and 88 which are formed on the opposed surfaces of the body portion 20*b* and 84 as shown in FIG. 8. The terminal wires 80 and 82 may be conveniently mounted in the body by putting a short duration relatively high amperage electrical current through the wires to melt the plastic while forcing them towards each other. Upon cooling, the heated plastic puddles around the wires and maintains them in strong physical engagement with the body and in electrical engagement with the respective contacts 86 and 88. The common terminal wire member 78 may be mounted similarly to terminal wires 80 and 82 if desired. One further distinction of the instant embodiment is that the lug 54*b* is formed with an undercut so that the aperture

46*b* fits over the lug and the blade means is retained by the force imposed by the tongue 44*b*. This is an exceedingly simple assembly operation requiring a simple positioning and no post operation is required to maintain the body and the blade means in assembled relationship.

Although specific embodiments of the invention have been shown and described, it is with full awareness that many modifications thereof are possible. The invention, therefore, is not to be restricted except insofar as is necessitated by the prior art and by the spirit of the appended claims.

What is claimed as the invention is:

1. A snap switch construction of minimum parts comprising in combination a one piece U-shaped switch body of flexible insulating material having first and second spaced apart substantially parallel portions integrally joined by a bight portion, fixed contact means fixedly mounted on said first portion, integral hinge means formed in said second portion intermediate the free end thereof and said bight portion, and snap action movable contact means having a portion fixed to said first portion of said switch body, means on said second portion of said switch body adjacent the free end and spaced from said hinge means for stressedly mounting another portion of said contact means whereby movement of said free end said second body portion causes snap action movement of said movable contact means relative to said fixed contact means.

2. A switch comprising switch body means integrally formed in one piece of relatively flexible thermoplastic insulating means, said body means having a thickness at one portion thereof to provide a relatively rigid portion and a lesser thickness in another portion to provide a relatively movable integral free end, said free end overlying said relatively rigid portion of said body means, flexible contact carrying electrically conductive blade means having a contact mounted on a first portion thereof, said blade means having a second portion fixed to said relatively rigid portion of said body means and disposed intermediate said free end and said relatively rigid portion of said body means, said blade means being formed with a third portion, means on said free end of said body means mounting said third portion of said blade means to impart a snap action movement to said first portion of said blade means, and fixed contact means mounted on said body means for engagement by said contact on said contact carrying blade means whereby movement of said free end of said body means causes snap movement of said contact on said contact carrying blade means.

3. A switch comprising one piece switch body means formed of tough thermoplastic insulating means having a rigid portion and at least one relatively movable integral free end connected to said rigid portion by a thin integral hinge means portion, flexible contact carrying electrically conductive sheet metal blade means having a contact mounted on a first portion thereof, said blade means having a second portion fixed to said rigid portion of said body means, said blade means being formed with a third portion means adjacent said free end of said body means engaging said third portion to impart a snap action movement to said first portion of said blade means, means on said free end for engagement by an actuator, and at least a pair of fixed contact means mounted on said body means for engagement by said contact on said contact carrying blade means whereby actuator engagement of said means engageable by an actuator causes movement of said free end of said body means to cause snap movement of said contact on said contact carrying blade means between said pair of fixed contact means.

4. The switch set forth in claim 3 wherein said third portion of said blade means is a tensioned portion also fixed to said rigid portion of said body means.

5. The switch set forth in claim 3 wherein said third portion of said blade means is an integral tongue struck

out of said blade means and put into compression engagement with said free end.

6. The switch set forth in claim 3 wherein said free end of said body means is the end portion of a substantially elongated arm portion disposed in substantially parallel spaced relation to said relatively rigid portion of said body means and in overlying relationship to at least a portion of said blade means.

7. The switch set forth in claim 6 wherein at least a portion of said free end is trappingly disposed below 10 said blade means to maintain operative engagement therewith.

8. The switch set forth in claim 3 wherein the pair of fixed contact means are printed on said body means and are electrically connected to terminal wires heat sealingly attached to said body means.
